Inventor
August Bostrom

UNITED STATES PATENT OFFICE.

AUGUST BOSTROEM, OF ROSELLE, NEW JERSEY, ASSIGNOR TO S. ROBERT SCHWARTZ, OF NEW YORK, N. Y.

SHADE MOUNTING.

Application filed July 24, 1924. Serial No. 728,041.

My invention relates to new and useful improvements in means for mounting reflectors or shades, particularly of the type disclosed in United States Letters Patent No. 5 1,486,319, granted to me March 11, 1924.

In the above patent there is described a 10 removably mounted reflector pivotally supported at both ends. To provide this mounting the reflector has at one end a keyhole-shaped slot which seats on a bushing provided on the lamp bracket, and at its other end with a hole through which passes a screw or stud carrying the parts necessary to 15 clamp the reflector in any desired position of adjustment.

My improvement consists mainly in providing a unitary device which I term a "shade lock" and which serves to permit ready mounting and removal and to prevent 20 accidental removal of the reflector from its mounting and to hold same in any adjusted position without extra manipulation such as locking. At any time the reflector may be 25 adjusted by simply setting it into the desired position. In this position the reflector remains until further adjustment is made. Co-operating with the shade lock are various other elements as will be fully described.

While my invention is shown applied to 30 a reflector it is obvious that it may have many other applications and it is understood that I do not limit myself to this specific disclosure.

Referring to the drawings: 35 Fig. 1 shows a portable electric desk lamp to which my invention has been applied.

Fig. 2 is a longitudinal cross-sectional view through the reflector and adjacent parts of the lamp shown in Fig. 1.

Fig. 3 is a view of the front elevation of 40 the shade lock.

Fig. 4 is a view in side elevation of the shade lock.

Fig. 5 is a view in rear elevation of the shade lock.

Fig. 6 is a cross-sectional view taken on the line $w-w$ of Fig. 5 in the direction of the arrows.

Fig. 7 is a view identical with that of 50 Fig. 6 except that the latch, later described, has been moved to a different position.

Fig. 8 is a view in perspective of the shade lock.

Fig. 9 is a bottom plan view of the shade 55 lock.

Referring to the drawings in detail, A is a reflector of the type described in my Patent No. 1,486,319, above referred to, B is a supporting bracket on which reflector A is pivotally mounted. The bracket can be raised or lowered by adjusting a swivel joint C 60 held in the lamp base D. The bracket carries an incandescent lamp socket E in which an incandescent lamp bulb F may be placed. Current is supplied by the wiring G passing through bracket B, made tubular for that purpose. 65

As far as described the construction is old and well-known. We now come to the features peculiar to my invention.

H is a shade lock pivotally mounted on the bracket B. It is of such shape that it will fit into the key-hole shaped slot L provided in reflector A. I is a pin carried by the bracket B which fits into hole K in the 75 reflector and provides a pivotal mounting for same. It will be clear that the reflector is thus pivotally mounted on the bracket on an axis defined by the pin I on the one hand and the shade lock on the other.

As described in my Patent 1,486,319, above referred to, the function of the key-hole shaped slot L is to permit ready removal of the reflector A by sliding the same laterally over the bracket B (accomplished 80 by moving the reflector to the left in Fig. 2 after slot L and the bracket are aligned). The shade lock H is so constructed that this lateral motion can take place when a part which I term the latch, which will be more 85 fully described, is depressed, but unless this latch is depressed it is impossible to move the reflector laterally to an extent sufficient to remove it from its mounting while yet permitting pivotal adjustment of the reflector. 90

The shade lock consists of a main frame 9, which in the preferred embodiment is a stamping, but which may also be formed by other processes such as casting and forging. This frame is provided with a cylindrical portion 10 adapted to fit into the rounded portion of the slot L in the shade and with a flange 10', which, as appears 100 from Fig. 2, serves to retain the shade in place while at the same time strengthening the frame. The frame 9 is further provided with a longitudinal portion comprising two steps 12 and 11 so as to form a recess for the parts 21 and 22. A tongue 14 is formed 105 110

in the main frame by stamping out a small section of the frame thereby leaving an opening 13. Similarly another tongue 16 and opening 15 are formed. The function of the tongues 14 and 16 is to limit the motion of the latch, as will appear later.

Extending from the portion 10 are a conical portion 17 and a cylindrical portion 19, both of which are broken into four sections 18 by slots 18. A collar 20 with ears 21 through which passes a screw 22 is soldered or riveted at its middle portion 20. Ears 21 and screw 22 are located within the recess formed by 12 and 11 so as to come within the contour of part 12 as presented in Fig. 3 and offer no obstruction to the passage of the slot L thereover. It is obvious that by adjusting the screw 22 the part 19 may be expanded or contracted. The part 19 seats on a cylindrical portion of the bracket B and pivots thereon. The expansion or contraction of part 19 diminishes or increases the friction between the parts and consequently the ease with which the shade lock may be moved.

The latch mechanism will now be described.

A spring 24, approximately U-shaped, is soldered or otherwise fastened at 25 to the main frame 9. To its free end is riveted at 27 a rigid piece 26 of angular shape having a lug 28 formed at one end and a portion 29 designed for manipulation at the other. The lug 28 is triangular in shape, the hypotenuse 30 being formed so that as the key-hole slot L of the reflector is pressed against it in the operation of mounting the shade the lug 28 will move inward against the action of spring 24 and will move outward again as soon as the reflector has passed beyond the lug. It is clear that the square shoulder of the lug will prevent removal of the reflector by motion in the reverse direction unless the lug 28 is first brought out the way by pressure on part 29 of the latch. The latch may also be manually operated when putting the reflector into place, instead of depending on the automatic action described. The purpose of tongues 14 and 16 is to limit the motion of the latch as will appear from the drawings, particularly 7 and 8.

Summarizing the functions of the various parts it will be noted that the reflector is readily placed on the bracket and that once in place it is held there until the latch 29 is operated to effect its release and that the reflector is at all times pivotally adjustable. The ease of adjustment is con-

trollable by the screw 22 which controls the frictional engagement between the shade lock and the bracket.

Among the advantages of the adjustability of the shade as described is the fact that it will stay in an adjusted position without being locked so that if the shade is suddenly struck by accident, it will not be marred nor broken by the blow but will simply turn about its pivot.

I claim:

1. In a lamp, a reflector mounted pivotally and capable of sliding laterally, supporting means for the reflector, retaining means pivotally mounted on the supporting means and a spring catch on the retaining means engaging the reflector to limit its lateral movement.

2. In a lamp, a reflector, mounted pivotally and capable of sliding laterally, supporting means for the reflector, retaining means pivotally mounted on the supporting means and comprising a shoulder engaging the reflector to limit its lateral movement in one direction and a spring catch engaging the reflector to limit its lateral movement in the opposite direction.

3. In a lamp, a reflector, supporting means for same, a key-hole shaped slot in one end of the reflector, retaining means pivotally mounted on the supporting means and fitting into the slot as to form a seat for the reflector and carrying locking means to prevent withdrawal of the reflector from its seat.

4. In a lamp, a reflector, supporting means for same, a key-hole shaped slot in one end of the reflector, retaining means pivotally mounted on the supporting means in adjustable frictional engagement therewith and fitting into the slot so as to form a seat for the reflector, said retaining means carrying locking means to prevent withdrawal of the reflector from its seat.

5. In a lamp, a reflector having a hole at one end and a key-hole shaped slot at its other end, a supporting bracket, a stud on the bracket engaging the hole in the reflector, a shade lock conforming in contour to the slot passing through the slot and frictionally and pivotally seated on the bracket, a shoulder on the shade lock for limiting the lateral motion of the reflector in one direction and a spring-actuated latch on the shade lock for limiting lateral motion of the reflector in the opposite direction.

In testimony whereof, I have signed my name to this specification.

AUGUST BOSTROEM.
